JEWELLED NECKLACE

Marianne Ostier, 40 Central Park S., New York, N.Y.

Filed Mar. 28, 1962, Ser. No. 69,473

Term of patent 14 years

(Cl. D45—16)

Fig. 1

Fig. 2

FIG. 1 is a plan view of the necklace.

FIG. 2 is a back view of a portion of the necklace, showing how the parts are linked together and

FIG. 3 is a cross-sectional view along the line 3—3 of FIG. 1.

The said necklace consists of jeweled reproductions of the State flowers of the fifty (50) States of the United States and the District of Columbia, in color and linked together with wire. The drawings are lined to indicate the color of the flowers of the respective states.

I claim:

The ornamental design for a jeweled necklace, as shown and described.
